Des. 240,430
Patented July 6, 1976

240,430

HAND-HELD SHOWER HEAD

Clifford E. Grube, Niles, Ill., assignor to
Associated Mills, Incorporated

Filed Aug. 18, 1975, Ser. No. 605,263

Term of patent 14 years

Int. Cl. D23—02

U.S. Cl. D23—35

FIG.1

FIG.2

FIG. 3

FIG. 4

FIG. 5

FIG. 6

FIG. 1 is a side elevational view of a hand held shower head showing my new design;

FIG. 2 is an elevational view taken from the side opposite that shown in FIG. 1;

FIG. 3 is a front elevational view thereof;

FIG. 4 is a rear elevational view thereof;

FIG. 5 is a bottom plan view thereof; and

FIG. 6 is a top plan view thereof.

The handle in FIGS. 3 and 4 has been broken away for convenience of illustration.

I claim:

The ornamental design for a hand held shower head, as shown and described.
